[57] CLAIM

The ornamental design for a combined outdoor cooking grill and griddle, as shown and described.

DESCRIPTION

FIG. 1 is a perspective view of a combined outdoor cooking grill and griddle showing my new design, the portions shown in broken lines are for illustrative purposes only and form no part of the claimed design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the left side elevational view being a mirror image of the right side view.
